UNITED STATES PATENT OFFICE.

WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

STARTING AND STOPPING MECHANISM FOR AUTOMATICALLY-PLAYED MUSICAL INSTRUMENTS.

1,304,971.

Specification of Letters Patent. Patented May 27, 1919.

Application filed March 16, 1917. Serial No. 155,171.

To all whom it may concern:

Be it known that I, WILLIAM E. HASKELL, of Brattleboro, in the county of Windham and State of Vermont, have invented a new and Improved Starting and Stopping Mechanism for Automatically-Played Musical Instruments, of which the following is a specification.

The object of the present invention is to provide starting and stopping mechanism for automatic musical instruments, particularly for pipe organs which use a perforated note sheet coöperating with an apertured tracker. The organization is such that when the musical composition has been completed, a special hole in the tracker will be uncovered and, as the result, the note sheet will be rerolled and the supply of air to the tracker box cut off, and, upon the completion of the rerolling, the rerolling mechanism will be cut out of action and the driving motor for the music roll will stop. The starting mechanism is arranged so that air will be supplied to the tracker box, and the note sheet motor will be set into action, this starting mechanism being coöordinated with the stopping mechanism so that both mechanisms properly act.

The invention is illustrated in the accompanying drawings, wherein—

Figure 1, is a diagram illustrating the several coöperating parts and showing their relation to each other. Fig. 2, is a plan view of the instrumentalities which are manipulated by hand in starting to play. Fig. 3, is an elevation of the starting mechanism. Fig. 4, is a horizontal section in the plane indicated by the line 4—4 in Fig. 3. Fig. 5, is a vertical section of the lower portion of the mechanism shown in Fig. 3. Fig. 6, is a vertical longitudinal section of a portion of the tracker box and of the motor which acts to couple either the take up roll or the music roll to the drive shaft. Fig. 7, is a vertical cross section of a lower portion of the take up roll and the lower portion of the tracker box. Fig. 8, is a detail view of terminals which coöperate with a switch carried by the take up roll. Fig. 9, is a vertical cross section of the tracker box and of a tube bar co-
operating therewith. Fig. 10, is a vertical cross section of the wind chest which supplies air to the motor which drives the music sheet. Fig. 11, is a vertical cross section of a wind chest which supplies air to the tracker box.

Fig. 12, is a horizontal section (in the plane 55 indicated by the line 12—12 in Fig. 13) of the regulating box which determines the amount of air supplied to the note sheet driving motor and hence the speed thereof, and which also supplies air to the motor 60 which couples and uncouples the take up roll and the music roll from the drive shaft. Fig. 13, is a vertical longitudinal section of the mechanism shown in Fig. 12, the section being in the plane indicated by the line 65 13—13 in Fig. 12. Fig. 14, is a vertical longitudinal section of the motor which restores the starting mechanism to original position and of the wind box through which the action of said motor is regulated. Fig. 15, 70 is a detail view illustrating the tempo mechanism.

The invention is shown as applied to a pipe organ in which air under pressure is employed in the various boxes and chests 75 illustrated, and in those chests wherein air is normally under pressure when the organ is in use, or is ready for use, the conventional symbol of a cross within a circle is employed to indicate the normal presence of 80 air under pressure.

A tracker box A, is shown in Figs. 1, 6, 7 and 9. The tracker box contains a tracker B, with two rows of holes, the music roll C, and the take up roll D. In Fig. 9, the note sheet a, is illustrated as extending from the music roll to the take up roll. The tracker box is provided with a sliding glass lid b, at the front which is closed when the organ is to be played so as to render the tracker 90 box airtight. After a music roll C, has been put in place and the leading edge of the note sheet has been attached to the take up roll, the lid is closed and the organ is ready to start. Starting involves supplying air to 95 the tracker box, coupling the take up roll to the drive shaft, and supplying air to the driving motor.

Supplying air to the tracker box.—A pipe 1 (Fig. 1) leads from the tracker box to an 100 air supply box E, which is shown in detail in Fig. 11. The pipe 1, communicates with a channel 2, having ports 3 and 4. Port 3, communicates with the supply box E, and port 4, communicates with the outer air. 105 Two valves 5 and 6, are connected together and to the movable board of a pneumatic 7, within the supply box. Valve 5, controls

the port 3, and valve 6, controls the port 4. The interior of the pneumatic 7, is in constant communication with the supply box E, through a bleed passage 8, and likewise is 5 in communication with an outlet pipe 9, having a large cross area as compared with the bleed passage. The outlet pipe 9, (Fig. 3) is closed normally (that is when the organ is not being played) so that the interior 10 of the pneumatic 7, is supplied with compressed air thus balancing the movable board of the pneumatic so that it drops by gravity, and the valve 5, closes the port 3, and the valve 6, opens the port 4, thus venting 15 the tracker box. In order to supply air to the tracker box, the outlet pipe 9, is vented to the open air so that the pressure within the interior of the pneumatic 7, is relieved, since air cannot be supplied by the 20 bleed passage 8, as rapidly as it is discharged by the outlet pipe 9. The result is that the excess pressure within the supply box E, collapses the pneumatic 7, so that its movable board rises thereby lifting the 25 valves 5 and 6, hence closing the port 4, and opening the port 3. Thereupon compressed air flows from the supply box E, through passage 2, and the pipe 1, to the interior of the tracker box ready to flow through any 30 hole in the tracker when an aperture in the note sheet registers therewith.

The outlet pipe 9, is normally (that is when the organ is idle) closed by a valve 10 (Fig. 3), which is carried at the lower end 35 of a sliding push rod 11, which at its upper end bears the word "Off" as shown in Fig. 2. This push rod 11, is connected by a centrally pivoted lever 12, to a second sliding push rod which at its upper end bears the 40 word "On" as shown in Fig. 2. When the organ is idle the push rod 13, is up and the push rod 11, is down closing the valve 10. To start the organ the push rod 13, is depressed, thereby elevating the push rod 11, 45 lifting the valve 10, venting the outlet 9, and hence admitting air to the tracker box. The push rod 13, is yieldingly maintained in both its upper and lower positions by means of a spring 14 bearing upon a double 50 cam 15 (Fig. 3), carried by the push rod 13.

Coupling the take up roll to the drive shaft.—The drive shaft F (Fig. 6), which is rotated through the pinion e, from the usual motor in a well known way, is mounted 55 to slide longitudinally and at its inner end it carries a pinion d, which is normally out of engagement with a gear e, which is permanently coupled to the shaft f, of the take up roll D. The particular intermediate 60 coupling shown between the gear e, and the shaft f, is to enable the take up roll to be lengthened or shortened to adapt it to receive note sheets of different widths, as set forth in Letters Patent of the United States

65 No. 1,250,165, December 18, 1917.

In order to connect pinion d, and gear e, the drive shaft F, is moved longitudinally to the left, as shown in Fig. 6. This longitudinal movement is accomplished by means of a pneumatic G, the movable board of 70 which has an arm 16 engaging an annular groove in a collar 17 fixed to the shaft F. The shaft F, is maintained in its normal position, shown in Fig. 6, by means of a spring 18, and the pneumatic G, is normally collapsed. The interior of the pneumatic communicates through a pipe 19, with the motor regulating box H, as shown in Figs. 1, 12 and 13. If compressed air is admitted to the pipe 19, the pneumatic G, is expanded, 80 thereby moving the shaft F, to the left (Fig. 6) and connecting pinion d and gear e.

As shown in Fig. 13, the pipe 19, communicates with a compartment 20, of the regulating box H. This compartment is 85 normally vented to the open air through port 21, and communication between it and the supply chamber 22, of the regulating box is controlled by a valve 23. The valve 23, is normally maintained closed by a spring 90 24. The stem 25, of the valve 23, slides in guides 26, and it is connected at its extreme outer end, as shown in Fig. 4, to a lever 27, pivoted at 28. This lever 27, has a roller 29, which is pressed by the spring 24, against 95 the periphery of a cam 30, on a vertical shaft 31, which at its upper end (Fig. 3) has a knob 32, for turning it by hand. Normally, the roller 29, bears upon the low part of the cam. When the knob 32, is turned, the high 100 part of the cam 30, encounters the roller and swings the lever 27 (Fig. 4), to the left thereby moving the valve 23 (Fig. 13) to the left and hence admitting compressed air from the supply chamber 22, to the compartment 20, and thence through pipe 19, to the pneumatic G (Fig. 6), thereby expanding 105 said pneumatic and coupling the take up roll to the drive shaft. This same movement of the stem 25, to the left, closes the venting 110 port 21, by a valve 33, loosely mounted on the stem 25. As shown in Fig. 13, the stem 25, has two buttons 34 and 35, and it carries a spring 36, between button 35, and the valve 33, which presses the valve 33, against 115 the button 34, while the stem 25, occupies its normal position. When the valve stem 25, is moved to the left by the cam 30, the valve 33, seats on the outer face of the box H, and is maintained yieldingly closing the 120 port 21, by the spring 36, since the throw of the cam 30 (Fig. 4), is greater than the normal distance between valve 33, and the end of the box, as illustrated in Fig. 13. Hence, during the playing of the composition, the 125 compressed air maintains the pneumatic G, expanded.

Driving the note sheet drive shaft.—When the organ is idle the note sheet drive shaft F, does not rotate. Hence, to start playing re- 130

quires setting this shaft in rotation. The shaft F, is rotated by a pneumatic motor of well known construction which is supplied with air from the regulating box H, through the pipe 37 (Figs. 1 and 13). The motor is not shown because well known. As shown in Fig. 13, the pipe 37, communicates with a compartment 38, of the regulating box H. This compartment 38, communicates with the supply chamber 22, through an elongated elliptical port 39, the contour of which is shown in Fig. 12. A slide valve 40, normally closes the port 39. This slide valve 40, itself has a port 41, which is adapted to register with the port 39, in order to supply air from chamber 22, to compartment 38. This slide valve 40, is connected by a rod 42, with a crank arm 43, on the shaft 31, as shown in Fig. 5. When the shaft 31, is turned by its knob 32 (Fig. 3), to start the organ, the crank 43, moves the rod 42, into proper position to move the slide valve 40, so as to bring port 41, into effective register with port 39, and, accordingly, air flows from chamber 22, compartment 38, and through pipe 37, to the motor which drives the shaft F.

When the slide valve 40, is in its idle position with its port 41, shut, as shown in Fig. 13, the compartment 38, is vented to the open air through the port 44. Coöperating with this port 44, is a valve 45, on a stem 46. An abutment 47, on the slide valve 40, bears against a button 48, on the stem 46, and maintains the valve 45, open. Consequently, any air leakage past the slide valve 40, into the compartment 38, will be discharged at the vent 44, so that there will be no accidental or premature running of the motor. When, however, the slide valve 40, is moved to the right (Fig. 12) the abutment 47, is moved away from the button 48, and a spring 49, causes the valve 45, to close the port 44.

After the musical composition has been completed the advance of the note sheet is stopped, the air is cut off from the tracker box, the note sheet is re-rolled upon the music roll, and the motor is stopped. All of this is accomplished automatically and primarily through a special hole in the tracker which is uncovered by a registering aperture in the note sheet.

Rewinding the note sheet.—The tracker B, has a number of extra holes in addition to those which control the sounding devices of the organ, as set forth in a companion application for Letters Patent of the United States Serial Number 143,750, filed January 22, 1917. One of these extra holes is utilized to set in action the rewinding mechanism. It is the hole indicated at 50, in Figs. 1 and 6, of the drawings. This hole is adapted to register with an aperture in a wide note sheet; this aperture appearing near the end

of the sheet after all of the note playing apertures have terminated. In case a narrow sheet is employed not equipped with apertures to control the sounding devices of the organ, this aperture may be in the form of a notch at the edge of the sheet. This hole 50, in the tracker communicates by a pipe 51 (Figs. 1 and 9), with a channel 52, in a tube bar I. This channel 52, communicates with the interior of a sliding inverted cup 53, constituting a pneumatic switch. This pneumatic switch is similar to the switch set forth in detail in United States Letters Patent No. 1,297,687, March 18, 1919. This pneumatic switch 53, is in permanent electric connection through wire 54, with one pole of an electric generator and it coöperates with a yielding terminal 55, which is in electrical communication with the opposite pole of the electric generator. Normally, as shown in Fig. 9, and during the playing, the pneumatic switch 53, is out of contact with the terminal 55. In the event, however, that an aperture in the note sheet registers with the hole 50, in the tracker, compressed air flows through the pipe 51, and channel 52, to the interior of the pneumatic 53, thereby lifting it until it makes contact with the terminal 55, thus closing an electric circuit. The wire 54, of this electric circuit leads to an electro-magnet 56, of the solenoid type (Fig. 14), which is inclosed within a wind box J, containing air under pressure. The core of this solenoid 56, is connected with a valve 57, which is located within a compartment 58, which communicates with the interior of the wind box by passage 59, and port 60. The valve 57, normally (when the solenoid 56, is not energized) closes a passage 61, which communicates by a pipe 62, with the interior of a "time" pneumatic 63, located within the wind box. The interior of this pneumatic 63, communicates with the open air through a bleed 64, of a much less capacity than the pipe 62. The movable board of the pneumatic 63, is joined by a flexible connector 65, with a valve 66, located in a channel 67, and controlling two ports 68 and 69. Port 68, communicates with the interior of the wind box J, and port 69, communicates with the open air. Normally the port 68, is closed, and the port 69, is open. The channel 67, communicates by a pipe 70, with the interior of a bellows K. The movable board of the bellows K, is connected by a link 71, with an actuator 72, consisting of a lever pivoted at 73. This actuator at its upper end is adapted to coöperate with a stud 74, on an endless chain L. This chain passes around an idle chain wheel 75, and also around a chain wheel 76 (Figs. 1, 3, 4 and 5), at the lower end of the shaft 31. When the tracker hole 50, is exposed and the pneumatic electrode 53 (Fig. 9), is lifted, the electric circuit is 130

closed which includes the solenoid 56. Thereupon, the core of the solenoid 56, is lifted and valve 57, is raised thus closing port 60, and establishing communication between the two passages 59 and 61. Thereupon air flows from the wind box through said passages and the pipe 62, to the interior of the pneumatic 63, thus equalizing the pressure inside and outside. Thereupon the movable board 63, and the pneumatic valve 66, drop by gravity, aided by the air pressure on the top of the valve 66. The dropping of the valve 66, closes the vent 69, and opens the port 68, so that air flows from the wind box J, through passage 67, and pipe 70, to the interior of the bellows K, thus expanding the bellows. The expansion of the bellows moves the upper end of the actuator 72, to the right (Fig. 14) thereby encountering the stud 74, moving the run of the chain L, to which the stud 74, is attached, to the right and hence rotating shaft 31, counterclockwise as the same is shown in Fig. 4. The first result is that the cam 30, is rotated to the position shown in Fig. 4, so as to bring its low part opposite the roller 29, on lever 27, whereupon the spring 24 (Fig. 13), moves the valve stem 25, to the right, thereby closing valve 23, and opening valve 33. Hence pipe 19, and pneumatic G, (Figs. 1 and 6), are vented and said pneumatic is collapsed by the spring 18. The result is that the drive shaft F (Fig. 6), is moved to the right thereby uncoupling pinion d and gear e. At the same time a crank pin g, fast on the shaft F, is brought into register with a crank pin h, on a sprocket wheel i, which is loose on the shaft F, so that as the shaft continues to rotate the sprocket wheel i, is rotated. This sprocket wheel i, is connected by a chain j, to a sprocket wheel k, on a shaft l, which is permanently coupled to the shaft m, of the music roll C, in the manner set forth in said Patent 1,250,165. Accordingly, rotation is imparted to the music roll C, and in the opposite direction to that in which it was rotated during the playing of the composition. Hence the note sheet is rewound. The backward rotation of the shaft 31, likewise through the crank arm 43 (Fig. 5), moves the slide valve 40. This movement of the slide valve first closes the port 41, but immediately reopens it wide so that the motor is run at high speed during the rewinding of the note sheet so as to rewind the note sheet in a minimum length of time.

Cutting off air from the tracker box.—The chain L, has a second stud 77, near the chain wheel 76, as shown in Figs. 1, 3 and 4. When the chain L, is moved by the actuator 72, stud 77, encounters the lower end 78, of a bell crank lever (Fig. 3) pivoted at 79. The upper end 80, is immediately below a padded button 81, at the lower end of a stem 82, carried by the push rod 13. When the stud

77, encounters the arm 78, and swings it to the right (Fig. 3), the upper arm 80, of the bell crank lever lifts the push rod 13, and hence through the lever 12, lowers the push rod 11, thereby closing the outlet pipe 9, through the valve 10. The result is that compressed air in the air supply box E (Fig. 11), flows into the interior of the pneumatic 7, through the bleed 8, thus equalizing the pressure inside and outside of said pneumatic so that its movable board and the valves 5 and 6, drop by gravity, aided by the air pressure on the top of the valve 6. The result is that the pipe 1, and the tracker box A (Figs. 1 and 9) are vented and there is no sounding of the organ during the re-roll of the music sheet.

The registration of the aperture in the note sheet with the hole 50, in the tracker is momentary and, in order to allow time for the described action to take place, the time pneumatic 63, shown in Fig. 14, is provided. As soon as the tracker hole 50, is again closed by the note sheet, channel 52, (Fig. 9) is vented at the bleed 83, and the pneumatic 53, drops thereby breaking the circuit which includes the solenoid 56 (Fig. 14). Thereupon valve 57, drops closing the passage 61, and pneumatic 63, is vented by the bleed 64, and the movable board of the pneumatic rises under the pressure of the air in the wind box J. In expanding, the movable board of the pneumatic 63, moves farther than the valve 66, thereby slackening the flexible connector 65. In again collapsing the movable board 63, moves upwardly about half way before tautening the flexible connector 65, and hence without lifting the valve 66, at all. Since the rise of the pneumatic 63, is slow, on account of the smallness of the bleed 64, the port 68, remains wide open long enough to permit the full expansion of the bellows K. As the pneumatic 63, completes its upward collapse, the tautened connector 65, lifts the valve 66, and closes the port 68, venting the passage 67, and the bellows K, to the open air through the port 69. The bellows K, might then be collapsed by a spring, but this is not essential because the bellows will be collapsed when the push bar 13, is again pressed down to start the organ again, and the shaft 31, is turned to open valve 23, and port 41. When the push bar 13, is thus pressed down its button 81, encounters the arm 80, of the bell crank lever thus rocking said lever and moving its lower end 78, to the left, thereby acting upon the stud 77, on the chain L, and hence moving that run of the chain to the left and hence partly swinging the actuator 72, to the left and hence partly collapsing the bellows. The subsequent turning of the knob 32, of the shaft 31, to bring the take up roll into action and to start the motor completes the forward move-

ment of the chain L, and hence fully collapses the bellows K.

Restoration of selecting mechanism to normal.—In the aforesaid companion application Serial No. 143,750, filed January 22, 1917, an automatic selecting mechanism under the control of the music sheet to select stops, couplers, etc., is described, and electrically controlled restoration means for restoring to normal idle position any stops, couplers, and the like which may be in action on the completion of a composition. This restoration means includes an electro-magnet. The restoration mechanism constitutes no portion of the present invention, but there is shown in the accompanying drawings the pneumatic control of the circuit which includes the electro magnet of the restoration mechanism of said companion application.

20 As shown in Fig. 14 the channel 67, communicates with the interior of a pneumatic switch 84 (similar to the switch shown in said Patent No. 1,297,687) which is in electric communication through a wire 85, with 25 said restoration controlling magnet. When compressed air enters the channel 67, the pneumatic switch 84 lifts and contacts with an electric terminal 86 which is in electrical communication with the opposite pole 30 of an electric battery to that with which the wire 85, is in communication. This closes the circuit and the restoration controlling magnet is energized. Thus the same aperture in the note sheet is utilized for the 35 restoration of the stop selecting mechanism, for rewinding the note sheet and for cutting off air from the tracker box.

Stoppage of note sheet driving motor.—When the note sheet is entirely rewound 40 upon the music roll C, it is desirable that the driving motor should stop and automatic means are herein provided for this purpose. The take up roll D, has a recess n, (Figs. 7 and 9), within which is pivoted at o, a metallic centrifugal switch M. As soon as the note sheet is wound once around the take up roll the centrifugal switch M, is maintained wholly within the recess n. When, however, the note sheet is entirely wound off from the 45 take up roll D, the centrifugal switch M, flies outwardly by centrifugal force as indicated in Fig. 7. The take up roll is then rotating in the direction indicated by the arrow in Fig. 7, and the centrifugal switch 50 passes between two spaced elastic electrical terminals 87 and 88 (Figs. 6 and 8), which are secured at their lower inner ends to the interior of the tracker box. These terminals 87 and 88, are connected respectively to 55 wires 89 and 90, which lead to opposite poles of an electric generator so that they constitute terminals of an electric circuit. It will be noted from Fig. 7, that the terminals 60 are curved but are not concentric with the 65 take up roll, being nearer the axis of the

take up roll at their free ends than at their fixed ends. The space between the terminals is large enough for the entrance of the shank of the centrifugal switch M, this space flaring at its mouth as shown in Fig. 8; but except 70 for this flaring mouth this space is narrower than the head of the centrifugal switch. Consequently, as the take up roll continues to rotate, after the centrifugal switch has entered the space between the terminals, the 75 head of the centrifugal switch bears with increasing pressure upon the yielding terminals. Not only is the electric circuit thus completed by the centrifugal switch, but also the terminals act as a brake to stop the 80 rotation of the take up roll. If the rotation of the take up roll is not stopped by the brake resistance, it is positively stopped by the head of the centrifugal switch coming in contact with the block 91, to which the 85 terminals are attached. Accordingly, the take up roll stops with the circuit completed.

One of the wires, as 89, leads, as shown in Fig. 1, to an electro-magnet 92, of the solenoid type carried by the wind chest N. This wind chest is shown in detail in Fig. 10. The core of the solenoid 92 is connected with a valve 93, which is normally down and closes a passage 94, leading to the interior 95 of the wind chest N. Within this wind chest is a pneumatic 95, the interior of which communicates by a passage 96, with a channel 97 (in which the valve 93, is located) and to the outer air by a vent 98. A passage 99, 100 communicates with the wind chest N, through a port 100, and with the outer air through a port 101. It also communicates by a pipe 102, with the compartment 22 (Fig. 13), of the regulating box H. The 105 movable board of the pneumatic 95, has a stem 103, with valves 104, and 105, coöperating respectively with the ports 100 and 101. The valve 93, normally closes the passage 94, and the interior of the pneumatic 110 is vented to the open air. Consequently, the movable board of this pneumatic is held upwardly by the air pressure within the wind chest N, so that the valve 105, is closed and the valve 104, is open, so that air flows from 115 the chest N, to the regulating box H, and from thence to the motor. When, however, the note sheet is entirely rewound the centrifugal switch M closes the circuit which includes the solenoid 89, the valve 93 is 120 lifted thus closing vent 98 and opening passage 94. Compressed air then enters pneumatic 95, and the two valves 104 and 105, and the movable board of the pneumatic drop aided by the pressure on the valve 105. 125 Consequently, air is no longer supplied to the motor which drives the shaft F, and the music roll C, ceases to rotate.

When the organ is to be played, it is necessary to turn the take up roll D, in the di- 130

rection opposite to the arrow shown in Fig. 7, in order to connect the leading edge of the note sheet to the take up roll, this being done in the usual way. This rotation of the 5 take up roll by hand disconnects the centrifugal switch M, from the terminals 87 and 88, thus breaking the circuit which includes the solenoid 92. Consequently, the valve 93 (Fig. 10) drops and closes passage 10 94, venting the interior of the pneumatic 95. Thereupon, the air pressure within the wind chest N, collapses the pneumatic 95, thus opening valve 104, and closing valve 105, so that air is again supplied to the regulating 15 box H, and the organ is ready to be started again.

Tempo regulation.—The shaft 31, has an exposed pointer 106 (Fig. 2), immediately below the knob 32, and this pointer swings 20 above fixed tablets 107 and 108, bearing the inscriptions "Reroll" and "Tempo" respectively, the tablet 108, also bearing a series 25 of numbers indicating speed. When the organ is stopped, the knob 32, should be turned so as to leave the pointer 106, in the position shown in Fig. 2, between the tablets 107 and 108. When the pointer is in this position, the crank arm 43, is in line with the rod 42, as shown in Fig. 15, and the port 41, 30 of the slide valve 40, is closed, as shown in Fig. 12. If now the shaft 31, should be turned in either direction the valve 40, will be moved forwardly and the port 41, will be opened to a greater or less degree depending upon the extent to which the valve 35 is moved. As already pointed out, when the motor K, expands (at the time that the rewinding of the note sheet begins) the shaft 31, is rotated so as to bring the pointer 106, opposite the "reroll" tablet 107, and to a 40 sufficient extent to leave the port 41, wide open so that the rerolling of the note sheet is at high speed. In starting the organ the user turns the knob 32, so as to bring the pointer 106, over the "tempo" tablet 108, and registering with the particular number 45 on the "tempo" tablet corresponding with the "tempo" number on the note sheet. The farther that the pointer is turned to the right over the "tempo" tablet the more the port 41, is opened and the higher the speed 50 of the note sheet driving motor.

Should the user wish to vary the pre-determined time momentarily it can be done 55 by the manipulation of the handle 109, shown in Figs. 2, 3 and 15. This handle is on a sleeve 110, surrounding the shaft 31. As best shown in Fig. 15, the sleeve 110, has a crank arm 111, which normally stands in 60 the indicated position there shown, with the handle 109 occupying the position shown in Fig. 2, between two fixed tablets 112, and 113, which are marked "Retard" and "Accel't." The crank arm 111, is connected by a rod 114, with a second slide

valve 115, shown in Fig. 12. This slide valve 115, has a port 116, of the illustrated flaring configuration. The port is narrow at its rear end and flares as it extends forwardly. When the port 41, is open, its effective area can be changed by moving the slide valve 115. If the handle 109, is swung to the left in Fig. 2, the valve 115, is moved forwardly thus bringing the narrow portion of its port 116, into register with the 70 port 41, hence restricting the amount of air supply to the motor and hence retarding it. On the other hand, if the handle 109, is moved to the right in Fig. 2, the valve 115, is moved rearwardly thus bringing the wide portion of the port 116, into register with port 41, thus permitting the passage of a larger quantity of air and hence accelerating the note sheet driving motor. When the user releases the handle 85 109, it is automatically moved to the idle intermediate position illustrated in Figs. 2 and 15, by springs 117 and 118, shown in Figs. 12 and 13. Each of these springs extends through a longitudinal slot 119 or 90 120 (Fig. 12), in the slide valve 115. If the slide valve 115, is moved rearwardly (that is to the left in Fig. 13) the spring 118, is put under increased tension while the spring 117 plays idly in the slot 119. 95 Then, when the handle 109, is released, the spring 118, restores the slide valve 115, to its intermediate position. The slide valve cannot overrun backwardly because it is checked by the spring 117, which acts in 100 opposition to the spring 118. Accordingly, the springs 117 and 118, between them restore the slide valve to its intermediate position. Likewise, if the slide valve 115, is moved forwardly, spring 117 will be put 105 under increased tension and spring 118 will play idly in its slot 120; and, when the handle 109 is released spring 118, will restore slide valve 115, to its normal intermediate position. Each spring 117 and 118, is 110 maintained in its normal position (shown in Figs. 12 and 13) by a stop 121.

Rewinding controlled by hand.—It is important that the rewinding of the note sheet should be under hand control. For example, after starting the playing of a composition it may be desired to stop it in the middle and to then rewind without completing the composition, or a note sheet may be used having no aperture or notch registering with the special hole 50. This is readily accomplished. To do so the user depresses the push bar 11 (Fig. 3), thereby closing the outlet pipe 9, by the valve 10. This results in venting the tracker box 120 through pipe 1, and vent 4 (Fig. 11), as already described. Hence, there is no further action of the sounding devices because no air can flow through the tracker holes. The user then turns the knob 32 (Fig. 2) so 125 130

as to carry the pointer 106, from over the "tempo" tablet 108, to over the "reroll" tablet 107. This turns the shaft 31, so that the low part of the cam 30 (Fig. 4), is opposite the roll 29 and, thereupon, the spring 24 (Fig. 13), closes the valve 23, and opens the valve 33, thus venting the pipe 19, and the pneumatic G (Fig. 6), so that the spring 18, moves the drive shaft F to the right thereby uncoupling the take up roll and coupling the music roll C, to the drive shaft F, so that the rewinding begins. After the rewinding has been completed the user turns the knob 32, so as to leave the pointer 106, between the "reroll" tablet 107 and the "tempo" tablet 108, as shown in Fig. 2, thereby, through crank 43, and rod 42 (Figs. 5 and 15), closing the port 41, of the slide valve 40 (Fig. 12), hence cutting off the supply of air to the note sheet driving motor; and opening the valve 45, through the abutment 46, on the slide valve 40, thereby venting the compartment 38, and permitting the escape of any air which may leak through the port 41. When the shaft 31, is in the position shown in Fig. 2 with the pointer 106, between the tablets 107 and 108, the roller 29, is on the high part of the cam 30, and close to the low part of the cam. Hence, any movement of the shaft in either direction from this point opens the port 41, and the rise of the cam in passing the roller 29, governs the coupling of the drive shaft to the take up and music rolls. The travel of the note sheet in either direction can be stopped at any time by turning the shaft 31, to the position shown in Fig. 2.

Operation.—To play the organ the user places the music roll in the tracker box and connects the end of the note sheet with the take-up roll D, and closes the lid b, (Fig. 9) of the tracker box. He then pushes down the push rod 13, (Figs. 2 and 3) thereby elevating push rod 11, (Fig. 3) and lifting the valve 10. This vents the pipe 9, (Figs. 3 and 11) and as the result the pneumatic 7, collapses thereby opening valve 5, and closing valve 6, and air then flows from the supply box E, through pipe 1, to the tracker box as shown in Fig. 1.

The user then by means of the knob 32, turns the shaft 31, clockwise, thus bringing the pointer 106, (Fig. 2) over the tempo tablet 108, to the proper position to secure the desired tempo. This turning of the shaft 31, through the cam 30, (Figs. 3, 4, and 5) acting upon the rod 25, closes the valve 33, (Fig. 13) and opens the valve 23, thereby admitting air from the regulating box to the compartment 20, from which it flows from pipe 19, to the pneumatic G, (Figs. 1 and 6) thereby shifting the drive shaft F, to such position as to connect it to the take-up roll D. Also, this forward

turning of the shaft 31, rocks the crank arm 43, (Figs. 5 and 15) from the straight line position, shown in Fig. 15, thereby through rod 42, moving the slide valve 40, (Figs. 12 and 13) so as to permit the flow of air from the regulating box H, through the pipe 37, to the motor which drives the shaft F. Thus the take-up roll is driven so as to wind the note sheet thereon and unwind it from the music roll.

After the composition has been played a special hole in the note sheet registers with the special hole 50, (Fig. 6) in the tracker. Thereupon air flows through pipe 51, (Fig. 9) to the pneumatic switch 53, thereby lifting said switch and making electric contact with the terminal 55. This closes an electric circuit which includes the wire 54, (Figs. 1 and 14) and the electromagnet 56, shown in Fig. 14. As the result, the valve 57, (Fig. 14) is lifted and air flows from the wind box J, through channels 59, and 61, and pipe 62, into the interior of pneumatic 63. This pneumatic then expands and the valve 66, drops closing the vent 69, and opening the port 68. Thereupon air from the wind box J, flows through passage 67, and pipe 70, to the bellows K, which expands. The expansion of the bellows acting through the lever 72, moves the chain L, and hence rotates the shaft 31, backwardly, that is, in the opposite direction to that imparted to it by the hand knob 32. This backward rotation of the shaft 31, removes the high part of the cam 30, from the roll 29, (Fig. 4) and, thereupon, the spring 24, (Fig. 13) closes the valve 23, and opens the valve 33, thus venting pipe 19. Thereupon pneumatic G, (Figs. 6 and 1) is collapsed by the spring 18, and the drive shaft F, is shifted so as to become disconnected from the take-up roll D, and to become connected with the music roll C.

Likewise, the backward turning of the shaft 31, rocks the crank arm 43, (Figs. 5 and 15) to the other side of its straight line with the rod 42, thus bringing the pointer 106, (Fig. 2) over the reroll tablet 107. The swing of the crank arm 43, momentarily closes the slide valve 40, (Figs. 12 and 13) and then opens it again so that air still continues to flow to the motor, and the shaft F, (Figs. 1 and 6) still continues to rotate but now it drives the music roll C, in the proper direction to unwind the note sheet from the take-up roll and to wind it onto the music roll.

Likewise, the movement of the chain L, by the bellows K, acts through the stud 77, to swing the lever 78, 80, (Fig. 3) thereupon lifting the push rod 13, and depressing the push rod 11. This closes the valve 10. Accordingly, as shown in Fig. 11, air from the box E, flows through passage 8, into the interior of the pneumatic 7, and the mov-

able board of this pneumatic drops closing valve 5, and opening valve 6. This vents the pipe 1, and the tracker box A, (Fig. 9) so that there is no sounding of the organ pipes during the reroll of the note sheet.

Also, as air flows from the box J, (Fig. 14) to the bellows K, the pneumatic switch 84, is lifted thereupon closing an electric circuit which includes the wire 85, thus putting out of commission the organ stops as set forth in pending application No. 143,750, filed January 22, 1917.

When the note sheet is completely unwound from the take-up roll the centrifugal switch M, (Figs. 7 and 9) flies out and makes contact with the terminals 87, and 88, thereby closing an electric circuit which includes wire 89, and magnet 92, shown in Fig. 10. Thereupon the valve 93, lifts and air flows from the chest N, into the interior of the pneumatic 95. The movable board of this pneumatic then drops closing valve 104, and opening valve 105. This vents the pipe 102, and hence cuts off the supply of air to the motor. Hence the music roll C, ceases to rotate. The lid b, (Fig. 9) of the tracker box can then be opened and the music roll can be removed and another inserted.

During the running of the motor it can be accelerated or retarded by the user manipulating the handle 109, (Fig. 15). By doing this the slide 115, is moved thereby varying the size of the air passage leading to the port 41, (Fig. 12) of the slide valve 40.

At any time during the playing of a composition the user can stop the playing by turning the knob 32, backwardly until the pointer 106, occupies the neutral position shown in Fig. 2. This will close the slide valve 40, (Fig. 13) and open the valve 45, thus venting the compartment 38. This stops any flow of air to the motor. Then by turning the knob forwardly again the playing would be resumed. Or, at any time either during the playing of the composition or upon the completion of a composition on a note sheet unprovided with an aperture 50 to register with the reroll hole 50, in the tracker, the user may stop the advance of the note sheet and effect its reroll by turning the knob backwardly until the pointer 106, registers with the reroll tablet (Fig. 2). This results in rerolling the note sheet onto the music roll. The user should also depress the push rod 11, (Fig. 3) by hand thus closing the valve 10, and venting the tracker box. When the rerolling is thus hand effected, at the close of the rerolling the centrifugal switch acts in just the same way as when the rerolling is automatically initiated.

In starting to play again, the connection 65 of another note sheet to the take-up roll

involves turning said roll forwardly and hence disconnecting the centrifugal switch M, from the terminals 87, and 88, and hence the opening of the valve 104, and the closing of valve 105, in Fig. 10, so that air again flows through the regulating box H, (Fig. 13). The depression of the push rod 13, on again starting to play moves the chain L, backwardly through lever 78, 80, (Fig. 3) and stud 77, thereby collapsing the bellows K.

When the user leaves the organ he should turn the take-up roll D, so as to disconnect the centrifugal switch from the terminals 87, 88. Since this results in connecting the regulating box H, with the supply wind chest N, the user should also turn the knob 32, so as to move the pointer 106, to the neutral position shown in Fig. 2. This closes the slide valve 40, (Fig. 13) and opens the valve 45, thus venting the compartment 38, and hence preventing any leakage of air affecting the motor. In this neutral position the roll 29, (Fig. 4) is on the low part of the cam 30, as shown in Fig. 4, so that the valve 23, (Fig. 13) is then closed and the valve 33, is open so that no air passes to the pneumatic G.

I claim—

1. A note sheet played organ having, in combination, a tracker with a special hole therein; a music roll; a take up roll; a drive shaft; means for alternately coupling the drive shaft to the take up roll and the music roll, said means including a pneumatic G and a spring; a regulating box H for the drive shaft motor having an air supply chamber 22 and a compartment 20 communicating therewith and with the open air; a pipe 19 leading from said compartment to said pneumatic; a channeled tube bar I; a pipe 51 leading from said special hole in the tracker to a channel in said tube bar; a pneumatic switch 53 communicating with said channel; an electric circuit governed by said pneumatic switch; a wind box J containing an electro-magnet in said electric circuit; a time pneumatic 63 within said wind box; an outlet bleed from the interior of said pneumatic; a valve 57 controlled by said electro-magnet and controlling the entrance of air from the said wind box to the interior of said pneumatic 63; an outlet channel 67 from said wind box having two ports one communicating with said wind box and the other with the open air; a valve 66 co-operating with both of said ports; a flexible connector between said valve and the movable board of said pneumatic 63; a bellows K; a pipe 70 leading from said channel to the interior of said bellows; an actuator 72 connected with said bellows; a rotatable shaft 31 having a chain wheel; an idle chain wheel; a chain L passing around said wheels having a stud adapted to be encountered and

moved by said actuator when said bellows is expanded; a valve 23 controlling the admission of air from said air supply chamber 22 to said compartment 20; and means between said shaft and said valve for controlling the movement of said valve.

2. A note sheet played organ having, in combination, a tracker with a special hole therein; a music roll; a take up roll; a drive shaft; means for alternately coupling the drive shaft to the take up roll and the music roll, said means including a pneumatic and a spring; a regulating box for the drive shaft motor having an air supply chamber 10 and a compartment communicating therewith; a pipe leading from said compartment to said pneumatic; a pneumatic switch communicating with said special tracker hole; an electric circuit governed by said pneumatic switch; a wind box; an electro-magnet in said electric circuit; a pneumatic within said wind box; a valve controlled by said electro-magnet and controlling the entrance of air from the said wind box to the interior 15 of said pneumatic; an outlet passage from said wind box having a port communicating with said wind box; a valve coöperating with said port; a connector between said valve and the movable board of said pneumatic; a bellows; a pipe leading from said passage to the interior of said bellows; an actuator connected with said bellows; a rotatable shaft having a chain wheel; a chain passing around said wheel having a 20 stud adapted to be encountered and moved by said actuator when said bellows is expanded; a valve controlling the admission of air from said air supply chamber to said compartment; and means between said shaft 25 and said valve for controlling movement of said valve.

3. A note sheet played organ having, in combination, a tracker with a special hole therein; a music roll; a take up roll; a drive shaft; means for alternately coupling the drive shaft to take up roll and the music roll, said means including a pneumatic; a regulating box for the drive shaft motor having an air supply chamber and a compartment communicating therewith; a pipe leading from said compartment to said pneumatic; a pneumatic switch communicating with said special tracker hole; an electric circuit governed by said pneumatic 45 switch; a wind box; an electro-magnet in said electric circuit; a pneumatic coöperating with said wind box; a valve controlled by said electro-magnet and controlling the entrance of air from the said wind box to the interior of said coöperating pneumatic; an outlet passage from said wind box having a port communicating with said wind box; a valve coöperating with said port; a connector between said latter valve and said 50 pneumatic; a bellows; a pipe leading from

said passage to the interior of said bellows; an actuator connected with said bellows; a rotatable shaft; mechanism between said shaft and said actuator whereby said shaft is rotated when said bellows is expanded; a valve controlling the admission of air from said air supply chamber to said compartment; and means between said shaft and said valve for controlling the movement of said valve.

4. A note sheet played organ having, in combination, a tracker with a special hole therein; a music roll; a take up roll; a drive shaft; means for alternately coupling the drive shaft to the take up roll and the music roll; a hand rotated shaft; means connecting the latter shaft and said coupling; means whereby when the hand rotated shaft is turned forwardly the take up roll is coupled to the drive shaft; a bellows; means between said tracker and bellows whereby when the special tracker hole is exposed the bellows is expanded; an actuator connected with said bellows and acting upon the hand rotated shaft to rotate said shaft backwardly thereby coupling the music roll to the drive shaft.

5. A note sheet played organ having, in combination, a tracker; a music roll; a take up roll with a recess therein; a centrifugal switch M pivoted within said recess and restrained from outward movement by the note sheet when wrapped around the take up roll but flying out beyond the periphery of the take up roll when the note sheet 100 is unwound therefrom; an electric circuit closed by said outwardly flying centrifugal switch; a note sheet drive shaft coupled to the music roll and take up roll in alternation; a wind chest N; an electro-magnet 92 105 coöperating with said wind chest and in said electric circuit; a pipe 102 leading from said wind chest and supplying air to the motor which rotates said note sheet drive shaft; a valve 104 controlling the supply of air from 110 said wind chest to said pipe; a pneumatic within said wind chest connected with said valve; a passage 96 leading from the interior of said pneumatic and communicating both with the open air and with the interior of 115 said wind chest; and a valve 93 governed by said electro-magnet and controlling the communication to said passage both from the wind chest and to the open air.

6. A note sheet played organ having, in combination, a tracker; a music roll; a take up roll; a centrifugal switch pivoted to the take up roll and restrained from outward movement by the note sheet when wrapped around the take up roll but flying out when the note sheet is unwound therefrom; an electric circuit closed by said outwardly flying centrifugal switch; a note sheet drive shaft coupled to said music roll and take up roll in alternation; a wind chest; an electro- 120 125 130

magnet coöperating with said wind chest and in said electric circuit; a pipe leading from said wind chest and supplying air to the motor which rotates said note sheet drive shaft; a valve controlling the supply of air from said wind chest to said pipe; a pneumatic connected with said valve, a passage leading from the interior of said pneumatic and communicating with the interior of said wind chest; and a valve governed by said electro-magnet and controlling the communication to said passage from the wind chest.

7. A note sheet played organ having, in combination, a tracker; a music roll; a take up roll; a centrifugal switch carried by the take up roll and restrained from outward movement by the note sheet when wrapped around the take up roll but flying out when the note sheet is unwound therefrom; an electric circuit closed by said outwardly flying centrifugal switch; a note sheet drive shaft coupled to said music roll and take up roll in alternation; and means controlled by said electric circuit to stop the drive shaft.

8. A note sheet played organ having, in combination, a tracker; a take up roll; a centrifugal switch carried by the take up roll and restrained from outward movement by the note sheet when wrapped around the take up roll but flying out when the note sheet is unwound therefrom; an electric circuit closed by said centrifugal switch; a note sheet drive shaft; and means controlled by said electric circuit to stop the drive shaft.

9. A note sheet played organ having, in combination, a tracker box; a lid closing the same; an air supply box; a pipe leading from the air supply box to the tracker box; two ports communicating with said pipe, one port also opening into the open air and the other into the supply box; a pneumatic within said supply box; two valves connected with the movable board of said pneumatic, and closing in alternation said ports respectively; a bleed passage connecting the interior of said pneumatic with said air supply box; an outlet pipe leading from the interior of said pneumatic; a valve normally closing said outlet pipe; and hand controlled means for opening said valve.

10. A note sheet played organ having, in combination, a tracker box; a lid closing the same; an air supply box; a pipe leading from the air supply box to the tracker box; a port communicating with said pipe and the supply box; a pneumatic; a valve connected with the movable board of said pneumatic, and adapted to close said port; a bleed passage connecting the interior of said pneumatic with said air supply box; an outlet pipe leading from the interior of said pneumatic; a valve normally closing said outlet pipe;

and hand controlled means for opening said valve.

11. A note sheet played organ having, in combination, a tracker box; a lid closing the same; an air supply box; a pipe leading from the air supply box to the tracker box; a port communicating with said pipe and with the supply box; a pneumatic; a valve connected with said pneumatic, and adapted to close said port; an outlet from the interior of said pneumatic; a valve normally closing said outlet; and hand controlled means for opening said valve.

12. A note sheet played organ having, in combination, a tracker; a music roll; a take up roll; a drive shaft; means for coupling and uncoupling the take up roll to the drive shaft by the longitudinal movement of the drive shaft; a normally collapsed pneumatic operatively connected with said drive shaft to slide said shaft; a regulating box H having a compartment 20 with two ports one leading to the air supply chamber of said box and the other to the open air; a pipe 19 leading from said compartment to said pneumatic; a guided valve stem 25 passing through said ports; two valves 23, 33, on said valve stem coöperating with said ports respectively; a spring 24 normally holding closed the valve 23 controlling the port between the air supply box and the said compartment, and maintaining the valve 33 open which controls the outlet port from said compartment; and a hand rotated shaft 31 having a cam 30 coöperating with the said valve stem to move it so as to reverse the position of said valves, whereby air is supplied to said pneumatic so as to expand it and couple the drive shaft to the take up roll.

13. A note sheet played organ having, in combination, a tracker; a music roll; a take up roll; a drive shaft; means for coupling and uncoupling the take up roll to the drive shaft; a pneumatic operatively connected to couple and uncouple said drive shaft; a regulating box having a compartment with two ports one leading to the air supply chamber of said box and the other to the open air; a pipe leading from said compartment to said pneumatic; a guided valve stem passing through said ports, two valves on said valve stem coöperating with said ports respectively; a spring normally holding closed the valve controlling the port between the air supply box and the said compartment, and maintaining the valve open which controls the outlet port from said compartment said latter valve being yieldingly mounted on the stem; and a hand rotated shaft having a cam coöperating with said valve stem to move it so as to reverse the position of said valves, whereby air is supplied to said pneumatic so as to couple the drive shaft to the take up roll.

14. A note sheet played organ having, in

- combination, a tracker; a music roll; a take up roll; a drive shaft; means for coupling and uncoupling the take up roll to the drive shaft; a pneumatic operatively connected to 5 couple and uncouple said drive shaft; a regulating box having an air supply chamber and a compartment with a port communicating with said chamber; a pipe leading from said compartment of said pneumatic; a valve coöperating with said port; and a hand rotated shaft having a cam coöperating with the said valve to open it, whereby air is supplied to said pneumatic so as to couple the drive shaft to the take up 10 roll.
15. A note sheet played organ having a note sheet drive shaft, in combination with means for supplying air to the driving motor of said shaft, said means comprising an air supply regulating box H, a pipe 37 leading therefrom to the driving motor; a slide valve 40 normally cutting off communication between said box and said pipe and having a port 41 adapted to establish communication 20 between said box and pipe when said slide valve is moved; a hand controlled shaft 31; a crank arm 43 on said shaft; and a rod 42 connecting said crank arm and said slide valve.
- 25 30. 16. A note sheet played organ having a note sheet drive shaft, in combination with means for supplying air to the driving motor of said shaft, said means comprising an air supply regulating box, a pipe leading 35 therefrom to the driving motor; a valve normally cutting off communication between said box and said pipe and having a port adapted to establish communication between said box and pipe when said valve is moved; a hand controlled shaft; a crank arm 40 on said shaft; and a rod connecting said crank arm and said valve.
- 40 45. 17. A note sheet played organ having, in combination, a note sheet driving shaft; a regulating box H having an air supply chamber 22 and a compartment 38; a pipe 37 leading from the compartment to the motor for said drive shaft, said compartment having an outlet port 44; in combination with a guided valve stem 46 extending through said outlet port, a valve 45 on said stem, a spring 49 acting to close said port through said valve, a button 48 on said valve stem; a slide valve 40 controlling the supply of air 50 to said compartment, an abutment 47 on said valve coöperating with said button to open the valve 45 controlling the outlet port from said compartment; a hand rotated shaft 31 having a crank arm; and a rod 42 connecting said crank arm and said slide valve.
- 55 60. 18. A note sheet played organ having, in combination, a note sheet driving shaft; a regulating box having an air supply chamber and a compartment; a pipe leading from the compartment to the motor for said drive 65
- shaft, said compartment having an outlet port; in combination with a valve stem, a valve on said stem, a spring acting to close said port through said valve, a button on said valve stem; a valve controlling the supply of air to said compartment, an abutment on said valve coöperating with said button to open the valve controlling the outlet port from said compartment; and means for moving said valve. 70
- 75 19. A note sheet played organ having, in combination, a note sheet driving shaft; a regulating box having an air supply chamber and a compartment; a pipe leading from the compartment to the motor for said drive shaft, said compartment having an outlet port; in combination with a valve for said port; a valve controlling the supply of air to said compartment and having means for holding open the valve controlling the outlet 80 port from said compartment; and means for moving said air supply valve. 85
- 90 20. A note sheet played organ having, in combination, a note sheet driving shaft; a regulating box having an air supply chamber and a compartment; a pipe leading from the compartment to the motor for said drive shaft, said compartment having an outlet port; in combination with two valves, one for said outlet port, and the other controlling the supply of air to said compartment; and means for closing one valve when the other is opened. 95
- 95 21. A note sheet played organ having, in combination, a tracker box; a lid closing said box; a tracker having a special hole adapted to register with an aperture near the end of the note sheet; a bellows K controlled in its action through said special hole in the tracker; an air supply box E; a pipe 100 1 extending from said air supply box to said tracker box; a valve 5 controlling the admission of air from said air supply box to said pipe; a pneumatic 7 within said air supply box connected with said valve, and the interior of said pneumatic communicating with the air supply box through a bleed passage 8; an outlet pipe 9 communicating with the interior of said pneumatic; a valve 10 controlling said outlet pipe; a lever 78, 80 operatively connected with said valve to close the same; a chain L actuated from said bellows; and a stud 77 on said chain coöperating with said lever, whereby when said bellows is expanded, the outlet pipe 9 and the valve 5 are closed. 105
- 110 115 22. A note sheet played organ having, in combination, a tracker box; a lid closing said box; a tracker having a special hole adapted to register with an aperture near the end of the note sheet; a bellows controlled in its action through said special hole in the tracker; an air supply box; a pipe extending from said air supply box to said tracker box; a valve controlling the ad- 120 125
- 130

mission of air from said air supply box to said pipe; a pneumatic within said air supply box connected with said valve the interior of said pneumatic communicating with the air supply box through a bleed passage; an outlet pipe communicating with the interior of said pneumatic; a valve controlling said outlet pipe; and a lever operatively connected with said valve and being moved by said bellows to close said valve.

23. A note sheet played organ having, in combination, a tracker box; a lid closing said box; a tracker having a special hole adapted to register with an aperture near the end of the note sheet; a bellows controlled in its action through said special hole in the tracker; an air supply box; a pipe extending from said air supply box to said tracker box; and means governed by said bellows for cutting off the supply of air from said air supply box to said tracker box.

24. A note sheet played organ having a tracker; a music roll; a take up roll; a drive shaft; a regulating box H having an air supply chamber 22 and a communicating compartment 38; a pipe leading from said compartment to the note sheet driving motor; a slide valve 40 normally closing the communication between said chamber and compartment and having a port 41 adapted to open said communication when said valve is moved; a hand rotated shaft 31 having a crank arm 43; a rod 42 connecting said crank arm and said valve, whereby in whichever direction said shaft is rotated to one side or the other of the position when the slide valve is closed, the port of said slide valve will be opened and to a greater or less extent depending upon the degree to which the shaft is rotated; in combination with a second compartment 20 communicating with said chamber; means for coupling the drive shaft to the take up roll and the music roll alternately including an actuating pneumatic G; a pipe 19 leading from said second compartment 20 to said pneumatic; a valve 23 controlling the admission of air from said chamber to said compartment 20; and a cam 30 on said shaft 31 controlling said valve, said cam having two concentric portions whereby the shaft can be rotated for the purpose of opening and closing the slide valve 40 to a greater or less extent so as to regulate the amount of air admitted to the note sheet driving motor without affecting the position of the valve 23 which controls the supply of air to the drive shaft actuating pneumatic.

25. A note sheet played organ having, in combination, an air regulating box having an air supply chamber and a communicating compartment; a pipe leading from said compartment to the note sheet driving motor; a valve normally closing the communication between said chamber and compartment

and having a port adapted to open said communication when said valve is moved; a hand rotated shaft having a crank arm connected with said valve, whereby in whichever direction the said shaft is rotated to one side or the other of the position where the valve is closed, the port of said valve will be opened and to a greater or less extent depending upon the degree to which the shaft is rotated; a second compartment 75 communicating with said chamber; means for coupling the drive shaft to the take up roll and the music roll alternately including an actuating pneumatic; a pipe leading from said compartment to said pneumatic; a valve controlling the admission of air from said chamber to said compartment; and a cam on said shaft controlling said valve, said cam having two concentric portions whereby the shaft can be rotated for the purpose of opening and closing the co-operating valve to a greater or less extent so as to regulate the amount of air admitted to the note sheet driving motor without affecting the position of the valve which controls the supply of air to the drive shaft coupling pneumatic.

26. A note sheet played organ having, in combination, an air regulating box having an air supply chamber and a communicating compartment; a pipe leading from said compartment to the note sheet driving motor; a motor valve normally closing the communication between said chamber and said compartment; a hand rotated shaft 100 having a crank arm connected with said valve, whereby in whichever direction the said shaft is rotated to one side or the other of the position where the slide valve is closed, the port of said slide valve will be 105 opened and to a greater or less extent depending upon the degree to which the shaft is rotated; a second compartment communicating with said chamber; means for coupling the drive shaft to the take up roll and the music roll alternately including an actuating pneumatic; a pipe leading from said compartment to said pneumatic; a valve controlling the admission of air from said chamber to said compartment; and a cam 110 on said shaft controlling said valve, said cam having a concentric portion whereby the shaft can be rotated for the purpose of opening and closing the motor valve to a greater or less extent so as to regulate the amount of air admitted to the note sheet driving motor without affecting the position of the valve which controls the supply of air to the coupling pneumatic.

27. A note sheet played organ having, in combination, a regulating box H having an air supply chamber 22 and a communicating compartment 38; a pipe 37 leading from said compartment to the note sheet driving motor; a slide valve 40 normally closing the 125

communication between said chamber and compartment and having a port 41 adapted to open said communication when said valve is moved; a hand rotated shaft 31 5 having a crank arm 43; and a rod connecting said crank arm and said valve, whereby in whichever direction the said shaft is rotated to one side or the other of the position where the slide valve is closed, the port 10 of said slide valve will be opened and to a greater or less extent depending upon the degree to which the shaft is rotated.

28. A note sheet played organ having, in combination, an air regulating box having 15 an air supply chamber and a communicating compartment; a pipe leading from said compartment to the note sheet driving motor; a valve normally closing the communication between said chamber and compartment; a hand rotated shaft having a crank arm connected with said valve, whereby, in whichever direction the said shaft is rotated to one side or the other of the position where the valve is closed, said slide 25 valve will be opened and to a greater or less extent depending upon the degree to which the shaft is rotated.

29. A note sheet played organ having, in combination, a tracker; a tracker box; a lid 30 closing the same; an air supply box; a pipe leading from the air supply box to the tracker box; two ports communicating with said pipe, one port also opening into the open air and the other into the supply box; 35 a pneumatic within said supply box; two valves connected with the movable board of said pneumatic, and closing in alternation with said ports respectively; a bleed passage connecting the interior of said pneumatic with said air supply box; an outlet pipe leading from the interior of said pneumatic; a valve normally closing said outlet pipe; hand controlled means for opening said valve; and automatic means controlled 40 by the note sheet and tracker for closing said valve.

30. A note sheet played organ having, in combination, a tracker, a tracker box; a lid closing the same; an air supply box; a pipe

leading from the air supply box to the 50 tracker box; a port communicating with said pipe and the supply box; a pneumatic; a valve connected with the movable board of said pneumatic, and acting to close said port; a bleed passage connecting the interior 55 of said pneumatic with said air supply box; an outlet pipe leading from the interior of said pneumatic; a valve normally closing said outlet pipe; hand controlled means for opening said valve; and automatic means 60 controlled by the note sheet and tracker for closing said valve.

31. A note sheet played organ having, in combination, a tracker; a tracker box; a lid closing the same; an air supply box; 65 a pipe leading from the air supply box to the tracker box; a port communicating with said pipe and with the supply box; a pneumatic; a valve connected with said pneumatic, and acting to close said port; an outlet from the interior of said pneumatic; a valve normally closing said outlet; hand controlled means for opening said valve; and automatic note sheet controlled means 70 for closing said valve. 75

32. A note sheet played organ having, in combination, a tracker with a special hole therein; a tube bar; a pipe leading from said extra hole in the tracker to a channel in said tube bar; a pneumatic switch communicating with said channel; an electric circuit governed by said pneumatic switch; a wind box containing an electro-magnet in said electric circuit; a pneumatic within 80 said wind box; a valve controlled by said electro-magnet and controlling the entrance of air from the said wind box to the interior of said pneumatic; an outlet passage 85 67 from said wind box having two ports one communicating with said wind box and the other with the open air; a pneumatic switch 90 84 communicating with said passage 67; and an electric circuit controlled by said pneumatic switch. 95

In witness whereof, I have hereunto signed my name.

WILLIAM E. HASKELL.
